Letters Patent No. 74,875, dated February 25, 1868.

IMPROVED APPARATUS FOR EVAPORATING SORGHUM-JUICE AND OTHER LIQUIDS.

The Schedule referred to in these Letters Patent and making part of the same.

TO ALL WHOM IT MAY CONCERN:

Be it known that I, HIRAM B. AVERY, of Bethel township, in the county of Branch, and State of Michigan, have invented certain new and useful Improvements in Pans for Evaporating Sorghum, Salt, &c., by steam; and I do hereby declare that the following is a full, clear, and exact description thereof, reference being had to the accompanying drawings, and to the letters of reference marked thereon, which form a part of this specification. In the annexed drawings, which make a part of this specification—

The letter A designates a steam-chest, upon the top of which is adjusted the evaporating-pan B. At one end of chest A is placed the pipe e, furnished with the gauge-cock C. The office of this pipe is to introduce steam into chest A. At the opposite end of the chest are two pipes, g and h. The pipe h will have the safety-valve n, designed to let off the surplus steam from the chest A. The pipe g will be furnished with a gauge-cock, i, to regulate the steam in chest A. In order to draw off the contents of pan B, when desired, there is made a hole, k, in one side of said pan, near its bottom, which can be closed by the slide J.

My apparatus is designed for evaporating sorghum, cider, or other saccharine juices.

In order to prevent the water, produced by condensed steam, from freezing in the chest A, it may be drawn from said chest by the pipe m, which is furnished with a stop-cock.

Having thus described my invention, what I claim, and desire to secure by Letters Patent, is—

The evaporator B, in combination with the steam-chest A, when said chest is furnished with pipes e, g, h, and m, substantially as set forth.

In testimony that I claim the foregoing as my own, I affix my signature in presence of two witnesses.
